BATTERY OPERATED TOOTHBRUSH HANDLE AND HOLDER CHARGER COMBINATION

Isadore Leyden, Shrub Oak, N.Y., assignor to Riviera
Appliance Corp., a corporation of New York

Filed Feb. 18, 1963, Ser. No. 73,620

Term of patent 14 years

(Cl. D9—2)

FIG. 4

FIG. 6

FIG. 3

FIG. 1

FIG. 5

FIG. 2

FIG. 7

FIG.8

FIGURE 1 is a front elevational view of a battery operated toothbrush handle and holder charger combination showing my new design, the broken line showing of the toothbrushes being included for illustrative purposes only;

FIGURE 2 is a side elevational view thereof;

FIGURE 3 is an elevational view of the other side thereof;

FIGURE 4 is a rear elevational view thereof;

FIGURE 5 is a top view thereof;

FIGURE 6 is a bottom view thereof;

FIGURE 7 is a perspective view thereof in exploded form showing the power unit removed from the base support therefor; and

FIGURE 8 is a top view of the base support.

I claim:

The ornamental design for a battery operated toothbrush handle and holder charger combination, substantially as shown and described.
